ETHYLIDENE DIACETATE AS BACTERIOSTAT IN COSMETIC AND OTHER COMPOSITIONS

Howard G. Zbornik, Caldwell, and Joseph J. Cahill, Jr.,
Colonia, N.J., assignors to Celanese Corporation of America, New York, N.Y., a corporation of Delaware
No Drawing. Filed Dec. 4, 1961, Ser. No. 156,992
21 Claims. (Cl. 167—85)

This invention relates to bacteriostat compositions. It more particularly relates to the use of ethylidene diacetate as a bacteriostat in certain applications.

These novel bacteriostat uses of ethylidene diacetate include cosmetics, toilet articles, household products, paints, coatings, paper products, foods, agricultural products, metal working fluids, plastics fibers and fabrics, and the like.

Ethylidene diacetate is an effective bacteriostat when employed in proportions from about 0.01% to 5% by weight of the product in the above noted uses. In cosmetics, food, toilet articles, household products, fabrics and the like, it is desirable to maintain the proportion of ethylidene diacetate toward the lower end of this range with about 0.01 to 0.03 weight percent being preferred. In various industrial uses, such as for example metal working fluids, agricultural products, some paper products, some paints, plastics and coatings, it is desirable to maintain the proportion of ethylidene diacetate at about 0.5 to 2 weight percent. Still other industrial applications of ethylidene diacetate as a bacteriostat permit the use of this material in proportions up to about 5 weight percent of the product. Of particular importance in this connection is the use of ethylidene diacetate to prevent slime formation in the paper industry and in the treatment of soil to control pests, bacteria and fungus growth.

Other specific bacteriocidal uses of ethylidene diacetate include shampoos, lotions, hair spray, deodorants, soaps, detergents, shaving creams, insecticides, insect repellants, oil and water base paints, facial and toilet tissue, sanitary napkins, cotton swabs, leather articles, cheese, cheese wrappings, garment bag coatings, metal cutting or grinding fluids, fiber sizing, particularly starch sizings, mouth wash, fabric conditioners, algaecide and others.

Soaps which are rendered bacteriostatic by the practice of this invention are generally characterized as being salts of fatty acids, particularly sodium potassium or ammonium salts, which have been compounded with other constituents, such as perfumes for example, to produce a marketable product. By detergents is meant anionic, cationic and nonionic detergents the formulations of which may in some instances include inorganic phosphates. Anionic detergents are exemplified by the commercial heavy duty household products such as that sold under the trademark Tide and are generally mixtures of alkyl aryl sulfonates and higher alcohol sulfates (e.g. C-12 alcohols). Cationic detergents generally find use in industrial cleaning particularly in the textile industry and are generally quaternary ammonium salts such as cetyl pyridinium chloride. Nonionic detergents are exemplified by ethylene oxide adducts of fatty alcohols or long chain aliphatic phenols (e.g. octadecyl phenol).

The following specific formulations serve to illustrate this invention but are in no way limiting thereon. All proportions are weight percent unless otherwise specified.

18 parts by weight polyoxyethylene adduct of castor oil having a specific gravity of 0.98 to 0.985, a viscosity of 305 cs., an hydroxyl value of 145 to 150 and 18 percent combined ethylene oxide;
18 parts by weight polyoxyethylene adduct of castor oil having 40% combined ethylene oxide, a viscosity of 230 cs., a specific gravity at 25° C. of 1.015 to 1.017 and an hydroxyl value of 108 to 115;
5 parts by weight tertiary nonyl polysulfide;
5 parts by weight petroleum sulphonate;
54 parts by weight dipropylene glycol;
0.02 part by weight of dye;
5 parts by weight ethylidene diacetate;
0.15 part by weight masking agent; and
40 parts by weight water.

OR IN 71/67

Two hundred milliliters of the emulsion as described above was mixed with one level teaspoon of degemerinated corn meal and the mixture allowed to stand in a dark cabinet at ambient temperatures for 30 days during which time no rancidity was observed. In contrast to this an identical metal cutting fluid, without ethylidene diacetate, when admixed with cornmeal as described above, showed rancidity in 12 to 24 hours.

It is to be understood that the foregoing detailed description is given merely by way of illustration and that many variations may be made therein without departing from the spirit of our invention.

Having described our invention what we desire to secure by Letters Patent is:

1. A water base metal working fluid containing ethylidene diacetate as a bacteriostat.
2. A fluid as claimed in claim 1 wherein said ethylidene diacetate constitutes about 0.01 to about 5 weight percent thereof.
3. A fluid as claimed in claim 1 wherein said ethylidene diacetate constitutes about 0.5 to about 2 weight percent thereof.
4. In the process of working metals using a water based functional fluid as the metal working fluid; the improvement which comprises the incorporation of ethylidene diacetate as a bacteriostat in said metal working fluid.
5. A polyoxyethylene adduct of castor oil-dipropylene glycol metal cutting fluid containing ethylidene diacetate as a bacteriostat.
6. A cosmetic containing as a bacteriostat therein ethylidene diacetate.
7. Paint containing as a bacteriostat therein ethylidene diacetate.
8. Soap containing as a bacteriostat therein ethylidene diacetate.
9. Paper containing as a bacteriostat therein ethylidene diacetate.
10. The process of preventing slime formation in paper-manufacturing equipment containing paper-making stock, which process comprises incorporating ethylidene diacetate into said stock as a bacteriostat.
11. The process of controlling earth bacteria and fungus which comprises treating said earth bacteria and fungus with ethylidene diacetate.
12. A fiber protected against mildew by impregnation with ethylidene diacetate.

13. A plastic having ethylidene diacetate applied thereto as a bacteriostat.

14. A cleansing cream having ethylidene diacetate therein.

15. A suntan lotion having ethylidene diacetate therein.

16. A shampoo having ethylidene diacetate therein.

17. A mouth wash having ethylidene diacetate therein.

18. A water base paint having up to about 5% ethylidene diacetate therein.

19. The process of controlling algae in running water which comprises adding ethylidene diacetate to said water.

20. The process claimed in claim 19 wherein said water is in a swimming pool.

21. A detergent having ethylidene diacetate admixed therewith.
